UNITED STATES PATENT OFFICE.

LOUIS H. MORIN, OF NEW YORK, N. Y., ASSIGNOR TO SOSS MANUFACTURING CO., INC.,
OF BROOKLYN, NEW YORK, A CORPORATION OF MAINE.

FRAME FOR VEHICLE WINDOW LIGHTS.

Application filed March 16, 1923. Serial No. 625,442.

My present invention relates to detachable frames for the transparent panels or "lights" of automobiles or the like, and aims to provide devices of the character designated above which shall be simple in construction, easy to assemble and disassemble for repair or replacement, which shall safely and securely retain and position the glass or other transparent panels, which shall also, with equal safety and security, retain their hold on the fabric in which the devices of the present invention are intended to be set or positioned, and which, while possessing all of the desirable and advantageous features of construction and usefulness specified above, shall be quite inexpensive.

By way of example, I shall, in the accompanying specification, describe, and in the annexed drawing show, several illustrative embodiments of the present invention. It is, however, to be clearly understood that my invention is not limited to the illustrative embodiments thereof herein shown and described for purposes of illustration only.

Referring to the drawings, wherein I have illustrated the aforesaid illustrative embodiments of the present invention:

Fig. 1 is a plan view showing the entire frame consisting of two frame members in assembled relation and comprising one of the aforesaid illustrative embodiments of the present invention;

Fig. 2 is a fragmentary sectional view taken along line 2—2 of Fig. 1, showing the frame before assembling with the glass or other transparent panel and the fabric of the vehicle top into which the frame is to be set;

Fig. 3 is a fragmentary sectional view, similar to Fig. 2, taken along line 3—3 of Fig. 1, showing the device after assembling;

Fig. 4 is a view similar to Fig. 2 of another embodiment;

Fig. 5 is a view similar to Fig. 3 of still another embodiment; and

Fig. 6 is a view similar to Fig. 3 of still another embodiment.

Referring to the aforesaid illustrative embodiments of the present invention, and more particularly to the drawing illustrating the same, especially Figs. 1, 2 and 3 of the drawing illustrating one of said illustrative embodiments, the device comprising said illustrative embodiment consists of a plurality of frame members of which the outer or female

frame member has been indicated by reference character 10, and the inner or male frame member by reference character 11. The outer frame member has an outer curved portion 12 for cooperation with the similarly curved portion 13 of the inner frame member 11. The portions 12 and 13 are oppositely curved, bent or rounded with respect to each other, and provide oppositely extending, overlapping binding portions. 60 The outer frame member 10 is provided with the outwardly curved lip 14 forming a part of said outer edge portion 12, as by being made integral therewith. Similarly, the inner frame member 11 has an inwardly curved lip 15 which forms a part of said outer edge portion 13, as by being made integral therewith.

The frame members 10 and 11 are provided with the inner edge portions 16 and 17, respectively. In order that the outer edge portions 11 and 12 may securely hold the fabric in which are set the frame and the glass or other transparent panel contained therein, I may knurl, corrugate or otherwise roughen a portion of the outer surface of the inner frame member, as indicated at 12' in Fig. 5 of the drawing, or else I may provide a portion of the inner edge of the inner frame member with teeth or serrations, as indicated by reference character 12" in Fig. 6 of the drawing. These roughened surface portions serve securely to retain the fabric in which the device is set or positioned. 90

In order to permit the ready detachment and removal of the device as a whole, and of the glass or other transparent panel forming a part of the same, I provide suitable fastening means, here shown as comprising a series of threaded bolts or screws 18 having the heads 19 which are welded, as at 20, to the portions of the outer frame member 10 adjacent the openings 21 in the outer frame member. The openings 21 in the outer frame member correspond to similarly positioned and oppositely disposed openings 22 in the inner frame member. The heads 19 of the fastening members 18 may be welded to the outer frame member 105 by any suitable means, especially by electric welding, preferably by electric spot welding. If the frame member to which the fastening means are to be attached is made of zinc or brass, so that the fastening 110

means 18, generally made of iron or steel, may not be readily welded thereto, I may provide the openings 21 with steel eyelets or grommets 21', as more clearly shown in Fig. 5 4 of the drawing. The provision of such an eyelet readily permits the welding of the head of the fastening means to the appropriate frame member.

The glass or other transparent panel, generally indicated by reference character 23, is provided with a suitable rubber or other resilient gasket or padding 24 surrounding the edges and part of the faces of the same. The fabric in which the device is set or within 10 in which it is positioned, is indicated by reference character 25, and is provided with a series of openings 26 to accommodate the shanks of the bolts or other fastening means 18. The fabric terminates in an inner edge portion 27 which may serve as an additional gasket or washer for safely and securely positioning the panels in the frame.

The device may be readily assembled as follows: The outer frame member 10, carrying the fastening means 18, is applied to the outer portion of the fabric of the vehicle top adjacent the opening defined by the edge 27 of such fabric. The glass or other transparent panel 23 carrying the rubber or other gasket 24 is suitably interposed within the outer frame member 10, and the inner frame member 11 is now applied to the inner side of the fabric 25, and nuts 28, or equivalent fastening members, are then applied over 20 the inner threaded ends of the bolts or other fastening means 18.

From the foregoing description it will be readily apparent that the device of the present invention is simple in construction, and easy to assemble or disassemble for the purpose of repair or replacement. The device also serves in a very efficient manner to retain and position the glass or other transparent panel with the necessary safety and security. Due to the manner in which the fastening members are arranged with respect to the frame member carrying the same, the device is unusually strong and will stand considerable wear. The provision of the rubber or equivalent resilient gasket for the outer edges of the glass or other transparent panel, and the use of the inner edge of the cloth or other fabric of the vehicle top as a gasket or washer, serve to give additional protection to the glass or other transparent panel. Where the portion of the inner surface of the outer frame member or of the outer surface of the inner frame member, or both, is knurled, serrated or otherwise roughened, the device serves all the more efficiently to retain the fabric between the frame members and thus helps to position the device safely and securely in the vehicle top.

65 The distinctive features of my invention

reside in the provision of two bodies or frame members which are substantially semi-circular in form in cross section, one of said members having an arc-shaped part extending into the other member and in 70 parallelism therewith, and both of said members being flanged; and further to the passage of the supporting fabric or body between the arc-shaped surfaces of the separate frame members arranged in parallelism, one of which surfaces or the members forming the same being fashioned to firmly grip the supporting body. Another distinctive feature of my invention resides in the specific means of mounting and fixedly 75 retaining the bolts in connection with one of the frame members or bodies by welding as described in order that said bolts or attaching devices constitute an integral part of such frame members, and it will be understood that while I have shown certain details of construction for carrying my invention into effect, that I am not necessarily limited to the structural details herein shown and described, and various changes 80 therein and modifications thereof may be made within the scope of the appended claims without departing from the spirit of my invention or sacrificing its advantages.

The present application is a continuation in part of, and an improvement over, the invention described and claimed in my co-pending application filed January 23, 1923, bearing Serial No. 614,387, and entitled "Detachable supporting frames and the like for removable transparent panels and similar devices."

What I claim as my invention is:

1. A window frame of the class described comprising two substantially similar frame members approximately semi-circular in form in cross section, said frame members being placed one upon the other, with the concave faces adjacent, the inner edges of said frame members being fashioned to receive and support a window panel and the outer edge of one of said members extending to form an arc-shaped member lying within the corresponding edge portion of the other frame member to form overlapped faces arranged in parallelism and the support of said frame being positioned between the overlapped faces of said members, and means for securing said members together to fixedly retain the support and window panel therebetween.

2. A window frame of the class described comprising two frame members substantially semi-circular in form in cross section, said frame members being mounted one upon the other with the concave faces thereof adjacent to form a frame substantially circular in form in cross section, the inner edges of said members extending to form means for supporting a window panel, and

the outer edge of one of said members being extended to form a part arc-shaped in form in cross section and lying within the adjacent part of the other member and to extend in parallelism therewith and between which and said first named member the supporting body is adapted to be placed, and means comprising devices passed through said members for securing the same together with said window panel and mounting body therebetween.

3. A window frame of the class described comprising two frame members substantially semi-circular in form in cross section, said frame members being mounted one upon the other with the concave faces thereof adjacent to form a frame substantially circular in form in cross section, the inner edges of said members extending to form

means for supporting a window panel, and 20 the outer edge of one of said members being extended to form a part arc-shaped in form in cross section lying within the adjacent part of the other member and to extend in parallelism therewith and between which 25 and first named said member the supporting body is adapted to be placed, means comprising devices passed through said members for securing the same together with said window panel and mounting body therebetween, and the outer face of the extending part of one of said members being fashioned to engage said supporting body to retain the same in fixed position.

In testimony whereof, I have signed my 30 name to this specification this eighth day of March, 1923.

LOUIS H. MORIN.
